UNITED STATES PATENT OFFICE.

ELLIS B. BURRELL, OF BALTIMORE, MARYLAND.

CASE FOR LICENSES, ETC.

Application filed December 10, 1926. Serial No. 153,787.

This invention relates to improvements in cases for licenses, etc., and has for its object to provide a simple, cheap and efficient device for carrying automobile licenses and similar articles and which can be readily and conveniently secured over a belt or pocket of the wearer.

The invention consists of the novel construction and arrangement of the parts and combination of the parts hereinafter more fully set forth in the following specification and pointed out in detail in the appended claim.

In the accompanying drawing—

15 Figure 1 is a plan view showing the case in the closed position.

Figure 2 is a plan view showing the case in an open position.

Figure 3 is an edge view of Figure 2.

20 Figure 4 is a detail plan view of the metal frame of the case.

Figure 5 is an edge view of Figure 4.

Referring to the accompanying drawings forming part of this specification and in which like reference numerals designate like parts throughout the several views thereof, 25 1 and 2 designate pieces of leather or other suitable material between which the metal frame 3 is secured by the stitches 4 on each side thereof and which hold the case in a rigid position. The front of the piece 2 is cut out at 5 to form pockets on both sides between the pieces 1 and 2. The flap 6 is sewed or otherwise secured to one side of the piece 1 and is adapted to fold over the pockets and secured in the closed position 30 by means of fasteners 7. The license case

or other similar articles may be carried in the pocket 5 or in the pocket at the rear of the pocket 5 between the pieces 1 and 2. 40 To the lower end of the frame 3 is secured a ring 8 to which is secured the chain 9 having a key ring 10 on its opposite end for the reception of any number of keys. The said frame 3 is also provided with another ring 45 11 to which is secured a hook 12 over which the key ring 10 is adapted to fit. When the hook 12 is not in use it may be caught in the ring 8 and held out of the way.

It will thus be seen that by having the 50 frame 3 between the pieces forming the case the latter will be held rigid and the rear ends of the case may be slipped over the belt or may be slipped over the pocket leaving front of the case on the outside of the 55 pocket.

Having thus described my invention what I claim is:

A case for licenses etc. comprising two pieces of suitable material secured together 60 at their edges and having pockets therebetween, a metal frame between said two pieces of material and having one end projecting below the other, a flap secured to said case and adapted to fold over the said 65 pockets, fasteners for holding said flap in position over said pockets, a chain secured to one end of said frame and having a key ring secured thereto, and a hook secured to the lower end of the frame over which said 70 key ring is adapted to fit.

In testimony whereof I affix my signature.

ELLIS B. BURRELL.
